SUCTION CLEANER

Bernard C. Becker, Canton, Ohio, assignor to The
Hoover Company, North Canton, Ohio, a cor-
poration of Ohio

Application February 10, 1936, Serial No. 63,131

6 Claims. (Cl. 15—16)

This invention relates to improvements in suction cleaners and more particularly to suction cleaners of the portable, handle maneuvered type and characterized by a wheeled casing supporting a motor driven fan for creating the suction applied at the nozzle into which the dirt-laden air is drawn and thence through the fan to be discharged into a dust collecting bag.

The object of the invention is to provide an improved construction and design for suction cleaners, embodying the assembly of the bottom plate forming the nozzle opening and the adjacent supporting wheels into a unit pivotally mounted on the cleaner casing for bodily movement relative thereto, and the pivotal mounting of said wheels on the bottom plate to permit their adjustment for varying the height of the nozzle above the floor.

A preferred embodiment of the invention will now be described in connection with the accompanying drawings in which:

Figure 1 is a general view in side elevation of the suction cleaner embodying the invention with portions broken away and shown in section;

Figure 2 is a bottom plan view of the forward portion of the cleaner;

Figure 3 is an enlarged detailed view of the latch member for the bottom plate as taken on line 3—3 of Figure 1;

Figure 4 is an enlarged detail view in vertical section through one end of the nozzle as taken on line 4—4 of Figure 1;

Figure 5 is a view in vertical section taken on line 5—5 of Figure 2, showing the bottom plate and carrier wheel assembly swung downwardly from the nozzle;

Figure 6 is a perspective view of the bottom plate and carrier wheel assembly removed from the cleaner and

Figure 7 is a bottom plan view of the cleaner similar to that of Figure 2, but with the bottom plate and carrier wheel assembly removed.

Referring to the cleaner in its general aspects, same comprises a casing 1, generally cylindric in shape with its axis extending horizontally. Integral with the casing 1 and extending transversely across its forward end, is the nozzle section 2 with its end portion extended somewhat beyond the casing 1 and having a downwardly facing opening or suction mouth.

The nozzle section 2 forms a chamber separated from the main casing 1 by a vertical wall 2a, the space immediately behind this wall being open throughout substantially one-half the bottom of the casing 1, as clearly shown in Figures

2 and 7; the other half forming a chamber or passage 1a extending rearwardly from the right hand end portion of the nozzle chamber and including the fan chamber 4 and exhaust passage 5 terminating in a rearwardly opening flanged outlet connection 5a to which a dust collecting bag 6 is attached.

The motor 7 is mounted lengthwise of the casing 1 with its axis horizontal and slightly eccentric to the axis of the casing. At one end of the motor is the fan 8, mounted directly on an extension of the armature shaft of the motor, the fan being enclosed within the fan chamber 4, forming a part of the front to rear extending passage 1a of the casing 1, while the major portion of the motor is exposed through the open bottom thereof.

Formed integral with the casing 1 and located on opposite sides thereof are laterally projecting housings 9 and 10 extending forwardly and downwardly with a slight convergence and finally merging with the end portions of the nozzle section 2 as clearly shown in Figure 1. These housings or integral lateral extensions of the casing 1 form passages concentric with the axis of the motor at their upper ends and opening at their lower ends into the nozzle chamber. The housing 9 on the right (Figure 7) is the outlet for the dirt laden air from the nozzle to the fan chamber, entering the latter through the circular opening or "eye" 4a concentric with the axis of the fan.

The corresponding housing 10 on the opposite side of the casing, as shown in Figure 1 and on the left in Figure 7, provides a conduit for a belt 11 engaging a drive pulley 11a on the end of the motor shaft and extending forwardly and engaging a rotary agitator 12 extending lengthwise of the nozzle chamber. The agitator 12 consists of a cylindric metal shell journalled on an axle 13, which in turn is supported at its ends in brackets 14, 14 secured to the end walls of the nozzle section 2, these brackets being so formed as to permit the agitator to be removed through the bottom of the nozzle for adjustments or repairs. On the surface of the agitator 12 is a pair of helically arranged projections or beater bars 12a and a pair of diametrically opposed brushes 12b, neither of which need be described in detail since the agitator per se has long been in common use. However, it is to be noted that the cylindric body of the agitator is grooved at 12c to provide a pulley for the belt 11.

The cleaner is supported upon wheels as already suggested. A pair of wheels 15, 15 suit-

- ably journalled on a bracket 15a attached or fixed to the underside of the casing form a caster-like support at the rear, while the front of the casing is supported by a pair of carrier wheels 16, 16 5 journalled at the outer ends of a transverse shaft or axle 17. The front wheels and axle are carried by the bottom plate as will now be described in detail.

Referring first to the bottom plate 18, the 10 same, as clearly shown in Figure 6, has somewhat the appearance of a shallow pan increasing slightly in depth transversely or from front to rear and with its bottom open to form a suction mouth surrounded by narrow lips which contact 15 the carpet around the opening. Extending from the upper rear edge of the body of the bottom plate is an extension 19 consisting largely of a pair of channel-like members 19a and 19b spaced inwardly a short distance from either end of the 20 plate and having their side edges as well as the remaining edges of the extension 19 upturned to form shallow marginal flanges. And finally, as integral parts of the bottom plate 18 is a pair of supporting arms 20, 20 whereby the same are 25 hinged or pivotally supported on the cleaner casing. These arms are preferably flat blade-like members having their forward ends bent at right angles and fastened rigidly to the underside of the rearwardly projecting channel extensions 30 19a, 19b, as by rivets or spot welding and pivotally mounted at their rear ends on pivot pins 21, 21 anchored in bosses 22, 22 adjacent the lower edge of the main casing 1 and directly beneath the central axis thereof.

35 For all practical purposes the bottom plate 18 may be considered as a one piece sheet metal stamping, although in actual practice it would be made up of several parts assembled into a unit as clearly shown in Figures 1 or 5 and in accordance with the accepted practice in sheet metal working.

Now, as clearly shown in Figure 6, the wheel supporting axis extends just rearwardly of the bottom plate proper 18 and directly beneath the 40 extension 19. Referring to the means employed for completing the assembly of the bottom plate and wheels, there is fixed at each end of the axle 17 an arm 23 extending radially and horizontally rearwardly therefrom, these arms having the 45 form of sheet metal straps looped around the axle at 23a and locked thereto as by tongues 17a on the axle to prevent relative rotation. At the other end of the arms 23 are smaller loops 23b which engage pivot pins 24, 24 carried by the 50 arms 20, 20 and extending laterally and outwardly at right angles thereto adjacent their forward ends.

By this mounting, the wheels with their axle 17 are capable of swinging bodily in an arc about 55 the coincident axes of the pivot pins 24, 24 and toward and from the bottom plate, although the latter movement, that is, in a downward direction, is resisted by a spring 25 (Figure 2), coiled about an extension 24a of one of the pivot pins 24, and having one end looped around the axle 17 and the other end hooked over the bottom edge of the adjacent arm 20.

The spring 25 thus acts constantly to press or force the wheels to swing bodily and toward the 60 underside of the bottom plate as clearly shown in Figure 1. However, the carrier wheels may be adjusted or shifted relative to the bottom plate and against the action of the spring 25 for the purpose of adjusting the height of the cleaner 65 nozzle relative to the floor level by the applica-

tion of a more or less standard arrangement of a nozzle height adjusting device (Figure 5). This adjusting device consists primarily of a vertically adjustable rod or stem 26 projecting downwardly through the top wall of cleaner casing 1 5 for contact with the axle 17 midway between its ends and a manually operated adjusting knob 27 mounted on the upper end of the stem, which is threaded so that in turning the knob in one direction or the other the stem is shifted endwise in a corresponding direction, either forcing the wheels downwardly and against the tension of the spring 25 or allowing the wheels to retract under the action of the spring. A visual indicator 28 for aiding the operator in adjusting the 15 nozzle to the desired height is a standard part of these adjusting devices and hence need not be described in detail. However, the stem 26 of the adjusting device is supported near its lower end in a bracket 29 mounted on the rear face of the 20 wall 2a at the back of the nozzle chamber, the stem 26 having a keyway 26a engaged by a key 29a in the opening in the bracket 29 through which the stem extends, to prevent the rotation 25 of the latter.

Now, since the bottom plate is capable of being swung bodily downward from its normal position in contact with the under side of the casing 1, it is necessary to seal the contacting edges against air leakage. Thus the upstanding flanges 30 surrounding the end and front edges of the bottom plate 18 are covered and enclosed by a sealing strip 30 preferably of rubber and fashioned in U-shape. However, the flanged edges of the rearwardly extended portion 19 of the bottom plate, including the two channel shaped rearward projections 19a and 19b, are not covered with rubber sealing strips but, as clearly shown in Figure 7, the bottom edges of vertical wall 2a conforms exactly with flanged edges on the plate and the former are covered with strips 31 of rubber. In other words, the sealing strips are carried in part by the bottom plate and in part by the casing, the result being an air-tight seal around the contacting edges of the bottom plate and 45 casing.

Thus when the bottom plate is in closed position, the rearwardly projecting channel portions 19a, 19b thereof form the bottom wall of the two passages leading rearwardly and upwardly on opposite sides of the casing 1, the 50 passage at the left (in Figure 7) accommodating the driving belt 11 for the agitator 12, whereas the passage at the right (somewhat wider and having a flared entrance) conveys the dirt laden air from the nozzle chamber into fan chamber and from thence into the exhaust passage 5 and finally into the dust bag 6.

And lastly, it is desirable to provide means for locking the bottom plate in a closed position, this being accomplished by a latch member 32 pivoted on a bracket 33 attached to the inner face of the forward lip of the plate and, projecting through a longitudinal slot 33a, has an external finger piece 32a which lies flush in a recess in 65 the bottom surface of the cover plate as is clearly shown in Figure 3. Adjacent the pivot of the latch member is a locking head 34 projecting from the inner surface of the front wall of the nozzle section 2 and engaged by the latch member to hold the bottom plate in closed position. Thus, when it is desired to release the bottom plate, the latch member 32 is swung downwardly 70 as shown in Figure 5.

The advantage of the herein described bottom 75

plate and carrier wheel assembly, aside from providing a convenient means of access to the agitator and nozzle chamber, materially simplifies the cleaner construction by utilizing the pivotally mounted bottom plate as the supporting structure for the carrier wheels, which are in turn pivotally mounted to cooperate with the nozzle height adjusting device.

Having disclosed the preferred embodiment of 10 the invention I claim as my invention:

1. In a suction cleaner, the combination of a casing having a nozzle extending transversely thereof and open at its bottom, a plate adapted to seat over the opening to said nozzle and slotted to form a suction mouth, said plate having arms extending rearwardly and pivotally connected with said casing whereby said plate may be swung downwardly from its normal position, 15 wheels for supporting said casing including an axle having arms extending radially therefrom and pivotally mounted on said plate, tension means acting to retain said axle in a predetermined position relative to said plate and means mounted on said casing and adapted to engage said axle for shifting the same bodily relative to said plate.

2. In a suction cleaner, the combination of a casing having a nozzle extending transversely thereof and open at its bottom, a bottom plate adapted to seat over the opening to said nozzle and adapted to form a suction mouth, said plate having arms extending rearwardly and pivotally connected to said casing whereby said plate may be swung downwardly from its normal position, 20 wheels supporting said casing including an axle extending transversely thereof and rearwardly of said nozzle, said axle having radially disposed arms pivotally mounted on said bottom plate supporting arms, tension means acting to force 25 said axle toward said plate and means mounted on said casing and operative to shift said axle and wheels bodily from said bottom plate and against the tension of said spring.

3. In a suction cleaner, the combination of a 30 casing having a downwardly opening nozzle chamber, a bottom plate normally adapted to fit over the opening of said nozzle chamber to form

a suction mouth and having rearwardly extending arms pivotally connected to said casing, and wheel supporting brackets pivotally mounted on said bottom plate and means carried by said casing for manually adjusting said wheel supporting brackets vertically with respect to said bottom plate when the latter is in its normal position.

4. In a suction cleaner, the combination of a 35 casing having a downwardly opening nozzle chamber, a bottom plate extending over the opening of said nozzle chamber and having a slotted portion forming the suction mouth thereof, said plate having arms extending rearwardly and pivotally connected to said casing, brackets 40 pivotally mounted on said bottom plate, wheels journaled at the free ends of said bracket, and means carried by said casing for adjusting said wheels vertically with respect to said casing.

5. In a suction cleaner, the combination of a 45 casing having a nozzle chamber, a bottom plate having a portion extending over said nozzle chamber and rearwardly extending arms pivotally connected to said casing, an axle extending transversely beneath said bottom plate rearwardly of said nozzle chamber, wheels journaled at the free ends of said axle, and axle supporting brackets pivotally mounted on said bottom plate adjacent the pivoted ends of said arm, and means for swinging said wheel supporting axle 50 and brackets bodily with respect to said bottom plate.

6. In a suction cleaner, the combination of a 55 casing having a downwardly facing nozzle chamber, a bottom plate forming the suction mouth of said nozzle chamber and having rearwardly extending arms pivotally connected with said casing, an axle having radially extending arms pivotally mounted at their ends to said bottom plate rearwardly of said nozzle chamber, 60 wheels journaled on said axle, and an adjusting screw carried by said casing in vertical alignment with said axle and adapted to contact the same to effect the vertical adjustment of said wheels relative to said casing.

BERNARD C. BECKER.
